UNITED STATES PATENT OFFICE.

PETER G. MACGREGOR, OF NEW YORK, N. Y., ASSIGNOR TO PYRENE MANUFACTURING COMPANY, A CORPORATION OF DELAWARE.

AUTOMATIC FIRE-EXTINGUISHER.

1,151,207.

Specification of Letters Patent. Patented Aug. 24, 1915.

Application filed February 13, 1913. Serial No. 748,103.

To all whom it may concern:

Be it known that I, PETER G. MACGREGOR, a citizen of the United States, and resident of the city, county, and State of New York, have invented certain new and useful Improvements in Automatic Fire-Extinguishers, of which the following is a specification.

This invention relates to a device or attachment adapted to be used in connection with a tank, especially in connection with dyeing or cleaning apparatus in which the material is cleaned in a tank containing naphtha, gasolene or similar fluids, which are very inflammable and frequently become ignited and result in a disastrous and destructive fire which destroys the machinery and the goods contained therein.

The object of this invention is to provide a simple device which may be used in connection with these tanks and by means of which a fire extinguishing compound is automatically injected into the interior thereof when a fire occurs therein.

In carrying out the invention I provide a receptacle for the fire extinguishing compound which is mounted upon the tank in such a manner as not to interfere with its ordinary use. The receptacle is provided with means operative whenever a fire occurs inside the tank for automatically injecting the compound and for vaporizing the same on the interior of the tank in order to more effectively and rapidly extinguish the fire.

In the drawings like parts in the several views have been given the same reference numerals.

Figure 1 is a sectional elevation of a washing or cleaning tank showing a device mounted thereon. Fig. 2 is a sectional side elevation of the upper portion of Fig. 1. Fig. 3 is a rear view of Fig. 2. Fig. 4 is an enlarged sectional view of the upper portion of Fig. 1, showing the device in its operative position.

A washing or cleaning tank is shown at 1 and is provided with a hinged cover 2 attached to the same. A receptacle 3 for a fire extinguishing compound is mounted upon the cover 2 and is provided with a lower or outlet valve 4 and an upper valve or air vent 5. These valves are connected together and operated by the valve stem 6 and the lever 7, which is pivotally mounted at 8 upon the cover 2 and formed with one end

projecting upwardly through an opening in 56 the cover 2 to the upper side thereof.

A lever 9 is pivotally mounted upon the pivot or hinge 10 of the cover 2 and is normally held in its open position by means of the spring 11, as shown in Fig. 4.

The lever 9 is provided with a latch 12 which when the lever is closed projects through an opening in the cover 2 and engages beneath the holding member 13 which is in turn held by a fusible member 14 attached thereto and passing around a pin 15 and attached at its opposite end to the pin 16 on the other side of the cover 2.

A wick 17 is carried in a suitable holder 18 against the inner surface of the tank 1 70 and extends from the upper to the lower portion of the tank into the naphtha or other cleaning fluid.

Should a fire occur a portion of the flame will be concentrated at the upper end of the 75 wick 17, which is positioned adjacent the fusible member 14, thus causing the same to be melted and releasing the member 13 which holds the latch 12. The latch 12 being beveled at the point where it engages 80 the member 13 will be readily released and the lever 9 will fly back to the position shown in Fig. 4.

When the lever 9 is in its closed position one end thereof engages the end of the lever 85 7 and holds the valves 4 and 5 in closed position but when the same is released by the melting of the fusible member 14, in the manner just described, the valves 4 and 5 will drop to their open position and release 90 the fire extinguishing compound from the receptacle 3, causing the same to be injected upon the vaporizing plate 19, which is mounted upon the under side of the cover 2. The vaporizing plate 19 having become 95 heated by the fire in the tank 1 causes the fire extinguishing compound injected thereupon to become rapidly vaporized in the form of a fire extinguishing gas which is distributed throughout the tank and is more 100 effective and operates with greater rapidity to extinguish the fire.

It will thus be seen that a very simple attachment is provided which will operate automatically when a fire occurs to inject 105 and vaporize the fire extinguishing compound in the form of a non-combustion supporting gas which is extremely efficient and

effective and operates with great rapidity in extinguishing the fire.

It will be understood that the details of construction may be changed to adapt the device for use with various forms of tanks, etc.

What I claim is:

1. A fire extinguisher comprising a support, a receptacle for a fire extinguishing compound mounted thereupon, means operative automatically when a fire occurs for causing the fire extinguishing compound to flow upon a vaporizer, and a vaporizer comprising a plate attached to the support and providing a space between it and the support and adapted to vaporize the compound.
2. A fire extinguisher comprising a support, a receptacle for a fire extinguishing compound mounted thereupon, means controlled by a fusible member adapted to operate automatically when a fire occurs adjacent said support for causing the fire extinguishing compound to flow from said receptacle, and a wick positioned adjacent said fusible member.
3. A fire extinguisher comprising a support, a receptacle for a fire extinguishing compound mounted thereupon, means controlled by a fusible member adapted to operate automatically when a fire occurs for causing the fire extinguishing compound to flow from said receptacle, a wick on said support extending from the bottom to the top adjacent said fusible member and means for supplying said wick with a highly inflammable liquid.

ate automatically when a fire occurs for 30 causing the fire extinguishing compound to flow from said receptacle, a wick on said support extending from the bottom to the top adjacent said fusible member and means for supplying said wick with a highly in- 35 flammable liquid.

4. A fire extinguisher comprising a support, a receptacle for a fire extinguishing compound mounted on said support, valves at the upper and lower ends of said receptacle operatively connected together, a lever pivotally mounted upon said support operatively connected to said valves and normally holding the same closed and adapted for automatically operating said valves 40 when a fire occurs adjacent said support for causing the fire extinguishing compound to flow to a vaporizer, and a vaporizer adjacent said support adapted to vaporize the compound. 45

Signed at New York city, in the county and State of New York, this 31st day of Jan., 1913.

PETER G. MACGREGOR.
